UNITED STATES PATENT OFFICE.

JOHN A. FROST, OF BROCKTON, MASSACHUSETTS, ASSIGNOR TO FROST & CHADWICK CO.,
OF CONCORD, NEW HAMPSHIRE, A FIRM.

OIL-CAN.

1,269,554.

Specification of Letters Patent. Patented June 11, 1918.

Application filed January 6, 1914. Serial No. 810,586.

To all whom it may concern:

Be it known that I, JOHN A. FROST, a citizen of the United States, residing at Brockton, in the county of Plymouth and 5 State of Massachusetts, have invented certain new and useful Improvements in Oil-Cans, of which the following is a specification.

My invention relates to an improvement 10 in oil cans, and more particularly to the spout thereof.

The object of this invention is to construct a spout with a valve therein, the stem of the valve to extend through the body, 15 and to rest against the bottom of the can, so that as pressure is exerted against the bottom of the can in the usual manner, the valve will be raised from its closed position, and the oil will be permitted to pass through 20 the spout.

A further object is to so construct the parts that the same spout, with the valve in place therein, can be adapted to different depths of can, and the same efficient result 25 will be obtained.

The invention consists of certain novel features of construction and combinations of parts which will hereinafter be more fully described and pointed out in the 30 claims.

In the accompanying drawings:

Figure 1 is a sectional view through an oil can with my invention applied; and

Fig. 2 is an enlarged sectional view 35 through the spout to better illustrate the structure of the valve.

Fig. 3 is a perspective view of the tubular valve.

The body of the can A is of the standard 40 type, and has the bottom 1 slightly dished in the usual manner.

The mouth opening 2 has screw threads formed therein, and the spout B is provided with screw threads 3 which fit into the 45 threads of the mouth 2 and hold the spout in place. This spout is formed of two members, the member 4 of which carries the screw threads, 3, and the member 5 tapered throughout its length to form a relatively 50 small outlet at 6.

A tubular valve 7 is located to slide in the member 4. This valve is tubular in its body portion, and at its outer end is closed as at 8. That part of the body portion adjacent the closed end is flared slightly, or

is made slightly tapered larger, as at 9, and the flared portion is of sufficient diameter so that it does not pass within the bore of the member 4. Openings 10, 10 are provided through the wall of the body of the valve at 60 a point adjacent to the flared portion. A yoke or cross bar 11 is secured across the inner end of the bore 4, and this cross bar is so positioned that it does not interfere with the free access of oil to the bore of 65 this member. A screw-threaded stem 12 is received through an opening formed in the yoke 11, and through screw-threaded orifice 13 in the end 8 of the valve. The stem 12 is screw-threaded throughout the greater 70 part of its length, and has a spring 14 received around that portion within the can and held against the yoke by a tension nut 15, which is adjustably received upon the stem 12. 75

A head 16 is formed on the extreme inner end of the valve stem to provide a contacting surface for the bottom 1 of the can. The operation of the device is as follows:

The valve stem 12 is screwed through the 80 orifice 13 to a sufficient extent so that the head 16 bears against the bottom 1 of the can. The spring 14 is of course held at the proper tension by the tension nut 15, so that the valve 7 will be held normally at a position with the flared portion 9 bearing against the outer end of the bore of the member 4, and this valve will thus be closed. 85

To place the oil where desired, the can is tilted, and the oil opening 6 is positioned to 90 direct the oil properly. The oil runs down into the tubular valve 7, but is prevented from escaping through the openings 10 by the engagement of the flared portion 9 with the bore of the member 4, which closes communication to the bore of the member 5. By exerting pressure on the bottom 1 of the can the valve stem is forced inwardly, and the valve is raised, so that the flared portion thereof is unseated from its seat against the member 4, and the openings 10 are brought into the bore of the member 5, thus permitting the free-flow of oil to the outlet opening 6. 100

When the pressure is removed from the 105 bottom 1 of the can, it is returned to its normal position by the natural spring of the dished portion, and the valve is returned to its closed position by the spring 14.

From the foregoing, it will be seen that 110

I have provided a spout which may be applied to the oil can when sold, or the spout might be sold as a separate article, and through the adjustment of the screw-threaded valve stem 12, could be adapted to use in cans of various sizes.

It is evident that slight changes might be made in the form of construction and arrangement of the different parts without departing from the spirit and scope of my invention, and hence I do not wish to be limited to the exact construction herein set forth, but:

I claim:

- 15 1. A spout for oil-cans comprising a screw-plug and integral discharge-tube, a spout fitted to and surrounding the outer end of the discharge-tube, a tube fitted within the discharge-tube and provided with orifices, a valve at the upper end of the said inner tube, a threaded stem connected with said valve, a spring mounted or sleeved upon the threaded stem, and a nut which screws
- 20

on the threaded stem for regulating tension of the spring.

2. A spout for oil cans comprising a screw-plug and a discharge tube connected thereto, a spout fitted to and surrounding the outer end of the tube thereby forming a valve seat, a tube fitted within the discharge tube and provided with orifices, a valve at the upper end of the said inner tube, a threaded stem connected with said valve, a substantially U shaped guide arranged integral with the screw plug and adapted to receive the threaded stem, a nut received upon the threaded stem and a spring arranged upon the stem between the guide and nut for maintaining a tension upon the valve.

In testimony whereof I affix my signature, in the presence of two witnesses.

JOHN A. FROST.
